UNITED STATES PATENT OFFICE.

MALCOLM U. WIKSTROM, OF CHARLEROI, PENNSYLVANIA, ASSIGNOR TO PITTSBURGH STEEL PRODUCTS COMPANY, OF PITTSBURGH, PENNSYLVANIA, A CORPORATION OF PENNSYLVANIA.

FURNACE.

1,217,251.

Specification of Letters Patent. Patented Feb. 27, 1917.

Application filed March 16, 1914. Serial No. 825,131.

To all whom it may concern:

Be it known that I, MALCOLM U. WIKSTROM, a citizen of the United States, and resident of Charleroi, in the county of Washington and State of Pennsylvania, have invented a new and useful Improvement 5 in Furnaces, and I do hereby declare the following to be a full, clear, and exact description thereof.

This invention has reference to furnaces and mechanism for charging the metal into the same and withdrawing it therefrom.

In the manufacture of tubing for instance, and more especially seamless tubing, it is necessary to anneal the tubes after they have been drawn, and heretofore it has been customary to insert the tubes one by one into the annealing furnace through the door arranged at the end of same, and after the tubes have been annealed it was customary to withdraw them one at a time so that the operation of introducing and withdrawing the tubes required a great amount of labor and time, while at the same time the time 25 that the door remained open during the charging of the furnace and withdrawing of the tubes resulted in a great loss of heat. By my invention I propose to obviate all this by providing for the charging and 30 withdrawing of a number of tubes at one time greatly reducing the labor and time heretofore required, and furthermore at a great saving in fuel.

In the accompanying drawings Figure 1 is a longitudinal vertical section of a furnace and with the charging apparatus shown in dotted lines therein, and in full lines outside of said furnace; Fig. 2 is a sectional plan view of the furnace with the 40 charging apparatus and the transfer mechanism in full lines; Fig. 3 is a cross-section on the line 3—3 Fig. 2.

In the drawing the numeral 1 designates the foundation of a suitable furnace with 45 the sides 2 and 3 and the top 4. The furnace is provided with the front opening 5 which is adapted to be closed by the door 6 which may be formed of a suitable casting with a refractory lining 7. The door 6 is 50 suspended by a suitable chain 8 connected up to any suitable mechanism (not shown) for raising and lowering the door.

One side of the furnace is provided with the apertures 9 arranged at intervals and 55 said apertures are adapted to be closed by

the doors 10 which are likewise formed of suitable castings with refractory linings 11. These doors are suspended by chains 12 which are connected with the counter-weighted arms 13 and which act to raise the 60 doors in their closed positions.

Within the furnace is the hearth 14 upon which the tubes or other articles to be annealed rest during the annealing process, and said hearth is provided with the grooves 65 15 which coincide with the apertures 9, and the bottoms of said grooves correspond with the bottoms of said apertures, for the reason more fully hereinafter set forth.

Arranged at intervals within the furnaces 70 and resting on the base 2 are the blocks 16 arranged at suitable intervals apart, and the upper corners of said blocks are rounded off as at 17. These blocks may be formed of metal castings and form the support for 75 the support or charging-table 18 which I will now describe in detail. This table consists of the angle-bars 19 connected by the cross-bars 20, said cross bars being formed of pairs of angles which combine to form 80 Z-bars, as clearly indicated in Fig. 1. The ends of the angle-bars 19 are slightly turned inwardly as at 21 so as to avoid liability of the said angle-bars interfering with the movement of said charging-table. The 85 charging-table rests on the frame 22 in front of the furnace, and said frame is made up of channel beams 22^a connected together and upon which the angle-bars 19 rest.

In the frame 22 is mounted the shaft 23 90 which is driven by the motor 24 and said shaft has the sprocket-wheel 25 with which the chain 26 engages. The chain 26 also passes around a sprocket-wheel 27 at the forward end of the frame 22. A hook 28 95 connected to the cross-bar 29 of the charging table is adapted to engage the sprocket-chain 26, said hook being pivoted to said cross-bar 29 so that it can be thrown into and out of engagement with the sprocket-chain 26. It is apparent that when the hook is in engagement with the chain and power is applied to drive said chain that the charging-table will be moved along the frame 22 into the furnace when the door 6 is raised, and the tubes 30 deposited on said platform will be carried into the furnace, the angle bars 19 engaging the blocks 16 and resting thereon, as clearly indicated in Fig. 3. The position of the charging table 100 105 110

when advanced into the furnace is indicated in dotted lines Fig. 1.

Extending parallel with the furnace are the tracks 31 on which the wheels 32 of the carriage 33 are adapted to travel. Power to drive the carriage 33 is obtained from the motor 34 which has the cog-wheel 35 meshing with the cog-wheel 36 on the driving axle 37.

10 The carriage 33 has the threaded sleeves 38 with which the vertical screw shafts 39 engage. The upper ends of the shafts 39 carry the beveled pinions 40 which are engaged by pinions 41 on the parallel shafts 42 and 42^a. Power is applied to drive one of the shafts 42 from the motor 43 which has the gear-wheel 44 meshing with the gear-wheel 45 on the said shaft 42. Power is communicated from the shaft 42 to the shaft 42^a by the sprocket-chain 46, whereby the shafts 42 and 42^a are driven simultaneously, and consequently the vertical screw-shafts 39 are raised and lowered equally and simultaneously.

25 Lifting bars 47 rest on the idle-rollers 48 and the pinions 49 which engage the rack-faces 50 on the lower faces of said lifting-bars, while the idle-rollers 50^a bear on the upper faces of said lifting-bars and guide the same as they move back and forth. The reciprocating movement of the lifting-bars 47 is accomplished by the engagement of the pinions 49 with the racks 50 of said bars, and power is transmitted to the pinions 49 from 30 the motor 51, a chain 52 connecting up the motor-shaft with the shaft 53 upon which the pinions 49 are mounted.

The lifting-bars 47 register with the apertures 9 in the sides of the furnaces and also 40 with the grooves 15.

When a bundle of tubes to be annealed are conveyed by a crane into position over the charging-table 18 the tubes are lowered to the said table and when the bundling-chains 45 are released the tubes will adjust themselves upon said table in parallel relation to each other, whereupon the door 6 is raised and power applied through the motor 24 to advance the charging-table into the furnace, 50 the hook 28 having been thrown into engagement with the chain 26, which advances the said table into the furnace along the frame 22, and as the said table enters the furnace the angle-bars 19 engage the blocks 16 and 55 advance over same until the table together with the pipes have been carried entirely into the furnace to the position indicated in dotted lines Fig. 1. The door 6 is then lowered. The carriage 33 is on the tracks 31 60 with the lifting bars 47 registering with the openings 39, whereupon the doors 10 are lifted, and said lifting bars having been previously adjusted to the proper height, the motor 51 is put in operation and the pinions 49 feed the bars through the apertures 9 into

the furnace, the bars passing below the tubes 30 and above the angle-bars 19 of the charging-table.

The motor 43 is then put in operation and through the connections described, the shafts 42 and 42^a are rotated simultaneously which will turn the screw-shafts 39 in the proper direction to lift the frame and the bars 49, whereupon the tubes 30 are lifted from the charging table to the position indicated in 75 full lines Fig. 3. The door 6 of the furnace is then opened and the hook 28 thrown into engagement with the chain 26. The motor 24 is started and the chain 26 draws the charging-table out of the furnace, back onto the frame 22. The door 6 is instantly lowered and immediately the lifting-bars 47 are lowered through the operation of the motor 43 and the bars dropped down into the grooves 15 in the furnace hearth until the 80 tubes rest on the hearth 14. The lifting-bars 47 are then withdrawn by the pinions 49, and the doors 10 close automatically. When the tubes have been properly annealed the doors 10 are again lifted and the lifting-bars 47 advance into the grooves 15 below the tubes, and said lifting-bars are then raised until the tubes are again brought in position indicated in full lines Fig. 3. The door 6 is opened and the charging-table introduced 85 into the furnace below the tubes whereupon the lifting-bars 47 are again lowered until the tubes rest upon said charging table. The lifting-bars are then withdrawn and the charging table is then drawn out of the 90 furnace with the annealed tubes resting thereon.

The carriage 33 may be driven along the track and the same lifting means may be employed in connection with a number of 105 furnaces arranged in line with each other.

While I have described my invention in connection with the annealing of tubes, I do not intend to limit it to this specific use, as it may be used for the annealing of rods or 110 other metal shapes, and in fact may be applied to any kind of a furnace to which it may be found applicable.

What I claim is:

1. The combination of a furnace, a longitudinally movable support for the metal adapted to move into and out of said furnace, and means introduced from the side of said furnace for receiving the metal from said support while within the furnace. 115

2. The combination of a furnace, a longitudinally movable support for the metal adapted to be moved into and out of said furnace, and lifting means introduced in the side of the furnace, and adapted to pass under the metal on said support. 120

3. The combination of a furnace, a hearth, a longitudinally movable support for the metal adapted to be moved into and out of said furnace and lifting means intro- 130

duced in the side of said furnace for lifting the metal from said hearth.

4. The combination of the furnace, a movable-support for the metal adapted to be moved into and out of said furnace, a frame at the side of said furnace, lifting-bars carried by said frame, said furnace having apertures for the entrance of said lifting-bars, and means carried by said frame for raising and lowering said bars.

5. The combination of the furnace, a movable-support for the metal adapted to be moved into and out of said furnace, a frame at the side of said furnace, lifting-bars carried by said frame, said furnace having openings for the entrance of said lifting-bars, means for raising and lowering said frame, and means for reciprocating said bars.

20 6. The combination of a furnace, a movable-support for the metal adapted to be moved into and out of said furnace, a vertically adjustable frame at the side of said furnace, lifting-bars carried by said frame, said furnace having apertures for the entrance of said bars, racks on said bars, pinions on said frame engaging said racks, and mechanism for driving said pinions.

7. The combination of a furnace, a movable-support for the metal adapted to be moved into and out of said furnace, a frame at the side of said furnace having threaded seats, screw-bars engaging said threaded seats, lifting-bars supported by said screw-bars, means for reciprocating said lifting-bars, and said furnace having openings for the introduction of said lifting-bars.

8. The combination of a furnace, a movable-support for the metal adapted to be

moved into and out of said furnace, a frame 40 at the side of said furnace, lifting-bars carried by said frame, means for raising said lifting-bars and for reciprocating same, said furnace having openings for the introduction of said bars, and counter-weighted 45 doors for said openings.

9. The combination of a furnace, a movable-support for the metal adapted to be moved into and out of said furnace, a carriage at the side of said furnace, lifting-bars supported by said carriage, said furnace having openings for the introduction of said lifting-bars, and means for raising and lowering said lifting-bars and for reciprocating same.

55 10. The combination of a furnace, a movable-support for the metal adapted to be moved into and out of said furnace, a furnace hearth having cross grooves formed therein, said furnace having openings in the 60 side registering with said grooves, and lifting-bars adapted to enter said openings and grooves.

11. The combination of the furnace, a hearth, a movable-support for the metal, 65 means for moving said support into and out of said furnace, a support above said hearth for said movable-support, and means for lifting the metal from said movable-support.

70 In testimony whereof, I, the said MALCOLM U. WIKSTROM, have hereunto set my hand.

MALCOLM U. WIKSTROM.
